UNITED STATES PATENT OFFICE.

LEO PAUL SEBILLE, OF CLEVELAND, OHIO.

GAS-GENERATING APPARATUS.

Application filed January 17, 1923. Serial No. 613,148.

My invention relates to an improved method and apparatus for producing the various forms of artificial combustible gas from bituminous coal, now employed for industrial and domestic purposes.

Practically all of the present combustible gases of commerce, that are made from bituminous coal, are produced by either coking the coal or by partial oxidation, either with air or steam or a mixture of the two. When air is employed the gas is called producer gas, and when steam alone is employed the gas is called water gas. When a mixture of air and steam is employed the gas is known as semi-water gas, and the gases made by coking a bituminous coal are usually known by the term "coal gas."

In producer gas, as now manufactured, there is present a relatively large amount of nitrogen and the combustible consists almost entirely of carbon monoxide. In the semi-water gas, the nitrogen content is relatively lower than in the producer gas, and there is present, as a combustible element, in addition to carbon monoxide, some hydrogen. Theoretically, the water gas consists of a mixture of carbon monoxide and hydrogen.

From a theoretical standpoint, any solid carbonaceous fuel may be used in the production of any of the above mentioned gases, but in practice these gases are made from high grade coals because the methods and the various forms of apparatus employed have rendered the use of low grade fuels impractical for the reason that such low grade fuels introduce difficulties of operation which have heretofore proven to be practically insurmountable.

It is well known that we have, throughout the world, numerous quantities of low grade fuels, as yet unmined, which have a fairly high calorific value, but which carry such a relatively large content of non-combustible material that it is not an economical proposition to transport them to the present centers of use, and the relatively high ash or non-combustible content renders their use impractical in the present forms of gas-producing apparatus. This situation favors the use, in the regions containing the deposits of relatively low grade fuels, of methods and apparatus capable of utilizing such fuels in the production of gases having a relatively high heating value, in order to make the transportation of such gases to the centers of use, an economical proposition.

It is one of the objects of the present invention to provide a method and apparatus especially adapted for utilizing low grade fuels, and, while my invention might be employed close to the centers of use of the gas, yet the production of the gas at these points would involve the transportation of a large amount of refuse from the mines to such centers of use and this could be avoided by manufacturing the gas in the vicinity of the mines and piping it to the centers of use as is common practice in connection with natural gas.

My invention has for a further object, the utilization of practically all of the combustible material in the fuel for useful purposes thereby avoiding the production of smoke and the losses now incident to burning bituminous coal in ordinary furnaces. It is impossible to secure the maximum efficiency in the utilization of bituminous coals, by burning them, in a raw state, in ordinary furnaces because such use of these coals inevitably results in the production of a certain amount of smoke and the loss of the tar and other by products which are more valuable for use in the chemical arts than as fuel.

Also, the present methods of making coal gas produce large quantities of coke of a kind for which there is only a limited market so that the gas making plants have difficulty in disposing of the coke. By my invention I utilize the carbon which ordinarily forms the coke, to make combustible gas for which there is a ready market.

It is a further object of the invention to provide a method and apparatus by which the volatile matter contained in the coal may be collected as by-products or may be utilized for the production of combustible gases. This double function is desirable under some conditions as it insures the complete utilization of the by-products as well as the carbon of the coal, thus replacing by a single unit that is more efficient and of less cost than present forms of apparatus.

With the present forms of apparatus for making water gas it is generally understood that fuels containing a readily fusible ash are not suitable but I am able to utilize such fuels by my method and in my apparatus because of the relatively low temperature at which the operation is carried out.

A further object of my invention is to provide a method and apparatus by which the

various desired forms of combustible gas may be produced, at will, from the same fuel.

I accomplish the foregoing objects of my invention by the method hereinafter described and with apparatus of which one form is illustrated in the accompanying drawing, this drawing being a side elevation of the apparatus with parts shown more or less diagrammatically and in section.

10 Referring to the drawing, it should be noted, at the outset, that the apparatus illustrated comprises a gas generator A that is externally heated by means of a combustible gas which may be produced in the generator 15 itself or from a liquid fuel or from an independently fired furnace or gas producer. In case an independently fired furnace is used for heating the generator A, the same may be either of the hand fired type or may utilize 20 a known form of mechanical stoker preferably adapted for burning low grade fuels. I have illustrated in the drawing heating means for the generator A that utilizes the gas produced in the generator or a liquid 25 fuel as will be hereinafter described in detail, but it will be understood that these may be replaced by any of the known forms of furnaces capable of producing heating gases.

30 The generator A is of the up-draft type and the gases produced therein are withdrawn from different portions of the generator, as will be described more in detail hereinafter. Some of the gases produced in 35 the generator A are passed through a superheated B which is heated by the heating gases leaving the chamber C which surrounds the generator A. The gases returning through the superheater B are delivered into the bottom of the generator A and supply the heat that is necessary, in addition to that supplied by the heating gases in the chamber C. The surplus of gases produced in the generator A are conducted through purifying 45 apparatus to the usual gas holder or the point of use.

The generator A is of upright cylindrical form and near the bottom is tapered, as indicated at 10, this tapered portion being surrounded by the annular chamber C to the lower part of which the heating gases are delivered from the furnaces or burners 11. The furnaces or burners 11 are supplied with combustible gases by the pipes 12 and 55 with air by the pipes 13, it being understood that the apparatus just referred to for supplying the heating gases to the chamber C may be replaced by any of the usual forms of furnaces for producing heating 60 gases. I have also shown, in connection with the furnaces or burners 11, supply pipes 14 for a liquid fuel which may be used in starting the apparatus. The oil pipes 14 have control valves 14' therein and may be 65 supplied, by a main 15, from any convenient

point of oil storage by the usual pumping apparatus that is commonly employed in connection with oil burners.

Below the tapered portion 10 of the generator A is an annular passage 16 which has communication with the interior of the generator through the ports 17 and with the space 18 below the chamber C by means of ports 19. The space 18 is in direct communication with the space 20 surrounding 75 the chamber C and formed between the outer wall 21 of the latter and the wall 22. The ports 17, as will be observed from the drawing, are so located as to be free from obstruction by ashes accumulating at the bottom of the generator and, in order to remove these ashes as they accumulate, suitable means must be provided which will prevent air from entering the lower part of the generator. I have illustrated as one of 80 such ash discharging means a screw conveyor 22' which may be operated from any suitable source of power and which is adapted to deliver the ashes into the receiver 23, a valve 24 being provided at the upper end of the receiver 23 to close off the latter from the interior of the generator when the valve 25, at the lower end of the receiver, is open in order to discharge the ashes that have 85 accumulated in the receiver.

The bed of fuel in the generator A may be from fifteen to twenty feet in depth and when the generator is in operation, the fuel will be practically exhausted of its volatile matter by the time it has descended to the level of the lower end 26 of the centrally arranged gas outlet pipe 27. From this it will be understood that the generator is ordinarily filled with fuel to a height several feet above the lower end of the pipe 27 and, for the purpose of supplying fuel to the chamber, any suitable form of charging apparatus may be used, and I have illustrated, for this purpose, a fuel receiver 28 which may be filled through the supply pipe 29 and from which the fuel is discharged into the generator by the pipes 30. The pipe 29 is provided with a valve 31 and the pipes 30 are each provided with a valve 32 in order to seal the upper end of the generator. When the receiver 28 is being charged the valves 32 will be closed and the valve 31 open, and when the generator is being charged from the receiver 28, the valve 31 will be closed and the valves 32 open.

The superheater B may consist of checker-work arranged to provide two separate passages 33 and 34 for gases so that heat may be transferred from the gases in one passage to those in the other. The heating gases from the chamber C are delivered, by means of the outlet 35, to the passage 33 through the superheater B and from the latter through a stack 36 to the atmosphere. 130

The stack 36 is preferably jacketed to provide an annular chamber 37 which has communication, by means of the ports 38, with the passage 39 which, in turn, has communication with the passage 34 through the superheater.

Arranged within the pipe 27 and spaced therefrom to provide an annular passage 40, is a pipe 41 which extends to a considerable distance below the lower end of the pipe 27 and serves as an outlet for certain of the gases produced in the generator A. The pipe 41 leads, preferably, to a dust collector 42 which removes the dust from the gases in the usual manner, and the gases are withdrawn from the dust collector 42 through a pipe 43 to the intake side of a blower 44 which discharges them through a pipe 45 into the passage 39. In order to supply gases to the burners or furnaces 11, I connect with the pipe 43, a branch pipe 46 with which the pipes 12 are connected, valves 47 being arranged in each of the pipes 12 to control the supply of gases thereto.

23. A blower 48, the intake 49 of which is open to the atmosphere, delivers air under pressure to the pipe 50 with which the pipes 13 for supplying air to the burners or furnaces 11, are connected. Valves 51 are provided in the pipes 13 for controlling the passage of air therethrough.

28. The blowers 44 and 48 may be operated from any suitable source of power and I have indicated these blowers as being driven respectively by the belts 52 and 53 from a power-driven shaft 54, but it will be understood that this arrangement of drive for the blowers is merely for purposes of illustration and that any other preferred form 40 of drive may be provided.

I provide in the pipe 41 a thermostatically-controlled valve, which is diagrammatically indicated at 55, and which is adapted to control the supply of steam from a main 56 to a pipe 57 which discharges into the annular chamber 37, surrounding the stack 36, as indicated at 58. It will sometimes be desirable to supply additional quantities of steam to the apparatus, over and above that which will be supplied through the thermostatically-controlled valve 55, and for this purpose, I provide a direct connection between the main 56 and the pipe 57, this connection being indicated at 59 and the supply of steam therethrough being controlled by the manually operable valve 60.

60. The discharge pipe 27, from the generator A may be led directly to the point of use of the gases but it is desirable, under certain conditions, to conduct the gases to suitable apparatus for removing the tars and ammonia therefrom and, for this purpose, I provide a branch 61 from the pipe 27

which leads to a point beneath the surface 65 of the water in the tar and ammonia collector 62. This collector 62 is preferably jacketed, as indicated at 63, and cooling water will be supplied to the jacket by means of the inlet and outlet pipes 64 and 65, respectively. A valve 66, at the bottom of the collector 62, operated by the floats 67, controls the discharge of the tars from the collector 62. From the drawing it will be obvious that when the level of the water in the collector 62 rises, the valve 66 will be opened and discharge a sufficient amount of contents of the collector to lower the level to a point which causes the floats 67 to close the valve 66.

70. A discharge pipe 68 conducts the gases from the interior of the collector 62 to a pipe 69 which has connection with the pipe 27 and which may also lead to a point of use or storage of the gases. Between the points of connection of the pipes 61 and 69, the pipe 27 is provided with a valve 70 and beyond the point of connection of the pipe 69 the pipe 27 is provided with a valve 71. A valve 72 is provided in the pipe 69.

75. A pipe 73 connects with the top of the generator A, as indicated at 74, and with the pipes 61 and has arranged therein a valve 75.

When the apparatus, just described, is in operation, the coal in the generator, above the lower end of the pipe 27, is coked by the heat in the chamber C and also the heat from the gases rising from the lower part of the generator, and either passing out through the pipe 27 or through the body of fuel surrounding this pipe, and the coal gas thus produced is drawn off through the pipe 73 and the pipe 62, into the tar and ammonia collector 62, the head of water on the lower end of the pipe 61 sealing this pipe and also putting a back pressure on the generator. From the foregoing it will be noted that the coking of the fuel surrounding the pipe 27 will be effected principally by the heat from the chamber C and from the gases in the pipe 27. By the time the coal descends to the level of the lower end of the pipe 27, the volatile matter will have been completely driven off and, from the level of the lower end of the pipe 27 to the level of the lower end of the pipe 41, water gas will be produced which will be drawn off through the pipe 27. Some of the gases produced below the lower end of the pipe 41 will be drawn off through this pipe, a portion of these gases being delivered to the pipes 12 and being used to supply the heating gases to the chamber C, the remainder of the gases discharged through the pipe 41 being delivered by the blowers 44 to the passage 39 where they are mingled with superheated steam and returned to the generator through the passage 34 in the

120
125

superheater, the space 20 surrounding the chamber C, the space 18 below the chamber C, the passage 16 and the ports 17. The superheated steam will be delivered to the passage 39 from the annular chamber 37 surrounding the stack to which steam will be supplied by the pipe 57. The mixture of superheated steam and gases returning to the generator, as above described, will be heated up in the superheater B, by the gases escaping from the chamber C and, on delivery to the interior of the generator, will supply to the fuel the heat required, in excess of that supplied from the chamber C, to operate the generator, the steam being decomposed and forming water gas in the generator A, which will be drawn off through the pipe 27, as previously described.

The valve 55 will be automatically controlled by the heat of the gases escaping through the pipe 41, to control the supply of steam to the apparatus so that as the heat of the gases escaping through the pipe 41 rises above a predetermined degree more steam will be admitted to the apparatus which will react on the fuel in the generator and tend to reduce the heat of the fuel therein. When the gases escaping through the pipe 41 are below a predetermined degree the valve 55 will so restrict the supply of steam as to permit an increase in the temperature of the fuel in the generator and in this way the temperature will be automatically controlled by the supply of superheated steam.

In starting the apparatus, fuel oil may be supplied by the pipes 14, which, being burned in the furnaces or burners, will supply the heating gases to the chamber C and heat will be transferred from the gases in the chamber C to the fuel in the generator A and effect a coking of the fuel. The operation of the blower 44 will cause the gases, thus generated, to be returned through the superheater B, to the generator until there is an accumulation of sufficient pressure within the generator to overcome the head of water on the lower end of the pipe 61. When this condition prevails the surplus of gas will escape through the collector 62, the valve 70 being closed and either the valve 71 or 72 being open. The recirculation of the gases through the generator, as above described, results in a rapidly rising temperature within the generator and when this temperature reaches a predetermined degree the valve 55 will be automatically actuated to supply steam to the apparatus and thereafter the apparatus will function in its normal manner.

The water gas discharged through the pipe 27 may be mixed with the coal gas drawn off through the pipe 73, by having the valve 70 closed and the valve 75 open.

The gases thus mixed in the pipe 61 will

pass through the tar and ammonia collector 62 and from there to the point of use.

Under some circumstances it may be desired to avoid the production of tars and ammonia and this may be done by closing the valve 75 which will cause the gases in the upper part of the generator to flow downward to the lower end of the pipe 27 and, in passing through the hot fuel, the tars will be broken up and converted into combustible gases.

The reaction that takes place in the lower part of the generator, below the level of the lower end of the pipe 41, is substantially to produce hydrogen and carbon dioxide with very little carbon monoxide, and this reaction takes place at a relatively low temperature which is below the usual temperature at which the ash content of the fuel is fused into large clinkers. Some of the gases produced in the part of the generator below the level of the lower end of the pipe 41, rises above this level and pass through the hot zone of the generator and escape through the pipe 27. In passing through this hot zone the carbon dioxide is broken down and carbon monoxide is formed.

According to my method the fuel is subjected to a relatively high temperature only so long as it contains a relatively large amount of carbon and when the carbon in the fuel is exhausted to a point which would permit the formation of clinkers, the temperature is reduced to a point below that necessary to form the clinkers. I am thus able to operate the generator continuously without the formation of troublesome clinkers.

From the foregoing it will be seen that I have provided an extremely flexible method of producing fuel gases from bituminous coal which is adapted to produce coal and water gas simultaneously, or a mixture of the two, and in which it is possible to utilize practically all of the volatile matters and carbon of the fuel.

Having thus described my invention, what I claim is:

In gas generating apparatus, the combination of a substantially cylindrical gas generating chamber having a vertical axis, means for externally heating said chamber, means for supplying fuel to the upper part of said chamber, means for withdrawing gases from the upper part of said chamber, a plurality of concentric pipes extending longitudinally through the upper part of said chamber and through which gases may be discharged, means for superheating the gases discharged through one of said pipes, and means for returning such superheated gases to the lower part of the chamber.

In testimony whereof I affix my signature.

LEO PAUL SEBILLE.
